LIQUID DISPENSING UNIT WITH VENTED TRAP

Jesse Harr, South Orange, N. J.

Application July 22, 1949, Serial No. 106,190

3 Claims. (Cl. 222—442)

1

This invention deals with valves for dispensing liquids and to valves which measure out a predetermined volume of liquid and then allow dispensing of said measured amount. Such valves are particularly valuable in dispensing sirups for soft drinks, cream for beverages, liquid soap, and the like.

The valves of the present invention are of simple construction, are very easy to clean, and certain ones may measure out, fairly accurately, the required volume of liquid, and they are self-emptying when in dispensing position.

The invention will be more clearly understood by reference to the drawing in which Figure 1 is an isometric view of the complete measuring and dispensing valve assembly installed, on the counter of a drug store, for example. A cross-sectional side view of the dispenser base, holding the liquid reservoir or container, together with a side view of the valve and tubular connection with the reservoir are illustrated in Figure 2, while Figure 3 shows a vertical cross-section view of the measuring and dispensing valve, the side view of which is shown in Figure 2. A top view of another modification of a dispensing valve is shown in Figure 4, while Figure 5 depicts a side view of the same valve. Similar numerals refer to similar parts in the various figures.

Referring again to the drawing, numeral 1 represents a beaker-shaped container, preferably of stainless steel or other durable, corrosion-resistant material, having an outwardly curved lip 2, acting as a support for the container, and a centrally disposed opening 4 in bottom 3, to which is welded or silver-soldered tube 5, preferably of the same material and shaped to project parallel to the counter 41 for some distance 5, thence downwardly in a U-shaped curve 6 which terminates at plate 7 to which it is soldered.

Base plate 7 of the valve is provided with two openings, 36 (into which leads feed tube 6), and 42 into which is fitted and welded discharge tube 19 having discharge or dispensing opening 39. Base plate 7 also has punched out near its edges, preferably three, equidistantly spaced bent bayonet clips 11 which fit into elongated holes 12 in lip 9 and cap 10 and which act as fastening means holding the base plate and cap together. Rubber or plastic gasket 8 is disposed between plate 7 and lip 9, acting as sealing means between the two surfaces which fit against it with a friction fit. Gasket 8 is provided with two holes superimposed over tube outlets 36 and 42.

Cap 10 is an inverted cup-shaped hollow member, carrying flared lip 9 which carries punched openings 12 through which bayonet clips 11 are inserted and, upon turning of cap 10 in a direction opposite to that of the bent prongs 11, they effect a tight locking of the cap to base plate 7. In the top of cap 10 is centrally disposed, in-

2

ternally flared opening 34 into which is inserted hollow cylindrical bearing or guide tube 40 which is soldered to the flare 34 and which houses oscillatable shaft 15. The lower end 43 of tube 40 is disposed high enough to clear flat valve plate 29 which is attached to shaft 15 at its center and which serves to direct the flow of liquid by way of hole 35 which is disposed in plate 29 in juxtaposition with entrance opening 36 or exit opening 42 (whichever is desired). When hole 35 is over opening 36 (as in Fig. 3), liquid from tube 6 enters space 30 until the level of the liquid reaches the level of the liquid in container 1. A vent tube 18 of small diameter is disposed in the upper part of cap 10 to allow egress of air which is displaced by liquid entering cap 10. Vent 18 is higher than the liquid level in container 1 so that no spillage of liquid can occur therethrough. When shaft 15 is turned until handle 16 touches stop 17 disposed on cap 10, hole 35 is in juxtaposition with opening 42 and the liquid then discharges through outlet 39.

Helical spring 31 is inserted over tube 40 and serves to impress a thrust on top 13 of cap 10 and on valve plate 29, thus keeping plate 29 tightly against rubber gasket 8. Also, shaft 15 is provided with one or several O-ring gaskets 32 which are seated in circumferential grooves 33 made on the surface of shaft 15. These gaskets serve to prevent leakage of liquid past shaft 15. Handle 16 has one end provided with a tapered thread for attaching it to shaft 15.

Container 1, tube 5 and valve 10 act as an integral unit which may be mounted in dispenser base 22 by inserting container 1 inside the hollow interior and allowing tube 5 to project through vertically cut slot 23 until lip 2 rests on upper edge 44 of base 22, when tube 5 projects between metal baffles 24 which serve to protect and center tube 5.

After container 1 and attached valve 10 are in place in base 22 (which is preferably of light metal such as aluminum, magnesium, or their alloys), the assembly is attached to counter 41 by turning thumb screw 28 in arm 26 of extension 25, until flat swivel 27 is tight against the bottom of counter 41, as are the bottom surfaces of base 22.

Then, bottle 45, containing the liquid to be dispensed, is inserted in inverted position in container 1, and ornamental cover 38 is slipped over dispenser base 22 (with projecting fins 21 acting as guides and supports therefor). The unit is then ready for the measuring and dispensing operation. To effect this, the operator turns handle 16 until hole 35 in valve plate 29 is over opening 36, in which case the liquid fills space 10. Then, handle 16 is turned until opening 35 is over 42, whereupon the liquid discharges through tube 19 and outlet 39. The operation is repeated for successive measured volumes of liquid.

The volume of liquid dispensed may be controlled by the diameter of valve 10 and height thereof. In the case of dispensing perishable liquids, such as cream, container 1 may be made of hollow evacuated vacuum-jar design, and the dispenser base, may be provided with insulated cooling jacket containing crushed ice or refrigerating coils.

Instead of vent 18 for discharging the air displaced by the liquid entering the valve, it is possible to employ a return line from tube 18 to the air space 50 of bottle or reservoir 45, in which case tube 5 could be connected directly to liquid reservoir 45. Also, it is possible to eliminate tube 18 and drill a hole through plate 7, gasket 8, plate 29 and up shaft 15 to a point near the top of cap 10 and drill a hole in the side of tube 40 and shaft 15 within cap 10, joining the aforesaid hole, thus venting the air therethrough from the inside of cap 10, through a tube soldered in base plate 7 (at the hole outlet) and into the air space of the reservoir.

Thumbscrews 55 may be disposed in side wall 56 of dispenser base 22, tightened against the outer wall of container 1 to anchor same in said dispenser base. Three of such screws are preferably used.

The valve shown in Figures 4 and 5 is employed only for dispensing a multiplicity of liquids, such as flavored syrup and soda water, or tea or coffee and water and cream. In this particular valve, the body design is similar to that shown in Fig. 3, but shaft 15 is pulled outwardly through opening 14, thus separating valve plate 29' (which, unlike plate 29, has no holes) from base plate 7. Plate 29' is provided with a rubber gasket liner 54 which is held firmly onto plate 29' by metal ring 55 which forms a friction fit with the edges of plate 29'. Gasket 54 seats tightly against ends 46 and 47 forming the openings of inlet tubes 50 and 51, respectively. When gasket 54 is pulled away from openings 50 and 51 (by pressing down toggle handle 16), it allows syrup to enter cap 10' from line 50, through opening 46 in base plate 9, and out through discharge pipe 19' located in the side of cap 10'. Also, it allows the simultaneous flow of soda water from smaller inlet tube 51, through hole 47 in base plate 9, into space 30 of the cap and out through discharge pipe 19' with the syrup. A mixing action takes place against the gasketed face of valve plate 29' which covers openings 46 and 47. When pressure on toggle handle 16 is released, coil spring 31' impresses its thrust action on plate 29' and shuts off the flow of liquids through lines 50 and 51. Any number of openings may be made in plate 7 for dispensing simultaneously any desired number of liquids.

Toggle handle 16 is pivoted at 48 on mounting 49 attached to top 13' of cap 10'. Toggle end 52 of handle 16 is spherical in shape and is disposed loosely in a similarly shaped recess 53 in the top section of shaft 15.

The juncture of cap lip 9 with base plate 7 is sealed against leakage with gasket 8', and lips 7 are provided with bayonet clips 11 fitting in openings 12. Also, as in the case of the valve in Fig. 3, shaft 15 is sealed in cylinder 40 against liquid leakage by O-ring gasket 32 in groove 33 in the wall of shaft 15.

In order to insure complete filling of cap 10 in Fig. 2, particularly when the liquid level in container 1 is low, it is preferable to keep the top 13 of cap 10 below bottom 3 of container 1.

It will be observed that the valves of the present invention are simple in design and require no tools but only a turn of the wrist for disassembly and cleaning.

5 I claim:

1. A liquid dispensing unit comprising a flat base having at least two openings radially disposed around a center, a resilient gasket on said base and having an open area in juxtaposition with the openings on said base, an inverted-cup shaped cap mounted over said gasket, a flat lip projecting from the edge of said cap adjacent the gasket in parallel relation to said base, fastening means for removably fastening said cap onto said base and tightly against said gasket, a centrally disposed opening in the top of said cap, a cylindrical tube having one end attached to said opening and disposed within said cap, a shaft disposed within said tube in liquid sealing relation thereto and having one end protruding out of said cap, a flat plate attached at its center to the end of said shaft disposed within said cap and of width large enough to cover said openings in said gasket, an opening in said plate superimposable over one of the openings in the gasket by rotation of said plate, spring means around said tube inside said cap for impressing a thrust upon said plate against said base openings, a long, small diameter vent tube projecting from the top of said cap, exteriorly disposed moving means for moving said shaft and said plate into open or closed position and comprising a handle on that end of the shaft protruding out of the top of said cap, and capable of rotating said shaft and said plate, a discharge outlet in said base below one of the openings in the gasket to serve as a discharge for the contents in said cap, a transfer tube attached to the opening in the base, other than the discharge opening, and a vertically disposed liquid container attached to the other end of said tube for feeding liquid therethrough.

2. A liquid dispensing unit according to claim 1 in which the container is a beaker-shaped self-centering vessel, and a hollow, open top, dispenser base, mountable to a counter and having a vertical narrow opening in its wall for accommodating said transfer tube, said hollow dispenser base serving to hold said container.

3. A liquid dispensing unit according to claim 2 in which the outer surface of said dispensing base has vertically disposed projecting ribs, and a thin hollow shell, open at the bottom, fitting tightly over said ribs, acting as a cover therefor.
